UNITED STATES PATENT OFFICE.

ARTHUR D. RAWLINGS, OF ST. LOUIS, MISSOURI.

MERCHANDISE-DISPLAY CARD.

1,032,024.

Specification of Letters Patent.

Patented July 9, 1912.

Application filed September 25, 1911. Serial No. 651,008

To all whom it may concern:

Be it known that I, ARTHUR D. RAWLINGS, a citizen of the United States, and a resident of St. Louis, Missouri, have invented 5 certain new and useful Improvements in Merchandise-Display Cards, of which the following is a specification containing a full, clear, and exact description, reference being had to the accompanying drawings, forming a part hereof.

My invention relates to improvements in merchandise display cards, and has for its object to provide a display card containing a transformation-picture device, which device is operated by means of a projecting arm, by the spectator.

In the drawings—Figure 1 is a front elevation of a device embodying my invention. Fig. 2 is a transverse sectional view of the same. Fig. 3 is a front elevation of the same, showing the picture transformed by the outward movement of the slide. Fig. 4 is a plan view of the picture-bearing slide.

As shown in the drawings, I provide a sheet 5, having merchandise-display spaces 6, and an opening 7, which is provided with two equal sized colored panes, 8 and 9 of different colors, for example, as illustrated in Figs. 1 and 3, the pane 8 is green and the pane 9 is red. Behind the panes 8 and 9, the picture-bearing slide 10 is mounted, it being provided with a projecting arm 11. Upon the slide 10 are imprinted superimposed pictures, of contrasting colors, one in the color of the pane 8, and the other in the color of the pane 9, the pictures being printed in the space indicated by the numeral 12.

It is obvious that when the arm 11 is thrust inwardly so that the space or square 12 registers with the pane 8, the green picture will be invisible, and the red picture visible; while an outward pull on the arm

11 will bring the picture-bearing space or square 12 into position to register with the pane 9, through which that picture will become visible which was invisible through the pane 8.

The slide 10 is mounted in the pocket 13 having a rear wall 14. Upon the front face of the rear wall 14, in the space registering 50 with the pane 8, is a suitable surface for advertising matter, which is visible through the pane 8 when the slide 10 is in its outward position (see Fig. 3).

Having thus described my invention, I 55 claim—

1. In a merchandise display card, the combination of a card provided with an opening, two variously-colored panes mounted in the opening, a picture-bearing slide mounted in 60 the rear of said panes and having two variously-colored pictures superimposed upon each other in a space adapted to register alternately with said panes, and a projecting arm whereby the movement of said slide is 65 controlled, substantially as described.

2. In a merchandise display card, the combination of a card provided with an opening, two variously-colored panes of equal size and shape mounted in the opening, a picture-bearing slide mounted in the rear of 70 said panes and having two variously-colored pictures superimposed upon each other in a space adapted to register alternately with said panes, and a projecting arm whereby the movement of said slide is 75 controlled, substantially as described.

In testimony whereof, I have signed my name to this specification, in presence of two subscribing witnesses.

ARTHUR D. RAWLINGS.
